UNITED STATES PATENT OFFICE.

ALEXANDER F. WARD, OF DETROIT, MICHIGAN, ASSIGNOR OF ONE HALF
TO THOMAS K. CHRISTIE, OF SAME PLACE.

HOOP-CUTTING MACHINE.

SPECIFICATION forming part of Letters Patent No. 392,651, dated November 13, 1883.

Application filed May 22, 1883. Serial No. 274,653. (No model.)

To all whom it may concern:

Be it known that I, ALEXANDER F. WARD, a citizen of the United States, residing at Detroit, in the county of Wayne and State of Michigan, have invented certain new and useful Improvements in Hoop-Cutting Machines, of which the following is a specification, reference being had therein to the accompanying drawings.

This invention relates to certain new and useful improvements in hoop-cutting machines of that class wherein a cutting-knife is employed to cut the hoops from the edge of a plank with the usual bevel given to hoops; and it consists in the construction, arrangement, and combination of parts hereinafter more particularly described, and then definitely pointed out in the claims.

In the drawings which accompany this specification, Figure 1 is a perspective view of my improved machine. Fig. 2 is a vertical central cross-section through the same. Fig. 3 is a side elevation thereof. Fig. 4 is a plan of the frame and bed with some of the operating parts removed. Fig. 5 is a diagram showing two alternate positions of the knife in cutting off the hoops, and Fig. 6 is a similar diagram on a larger scale.

A is the frame which supports the operating parts of the machine. B is a bed-plate supported thereon, and C are a series of upwardly-projecting flanges, the upper edges, D, of which form a table, upon which the plank from which the hoops are cut is supported and fed by the operator under the reciprocating knife E, which cuts off the edge of the plank to form bevel-hoops. Below the cutting-edge of the knife a cutting-block, F, is secured in the bed, preferably adjustably and removably, such as by means of the clamping-plates G, which are secured by the bolts *a* to the frame of the machine. The cutting-block F is preferably made in short lengths of wood, so as to be more easily adjusted in relation to the cutting-edge of the knife.

The knife is adjustably secured in the usual manner to the knife-head H, which extends longitudinally the whole length of the table, and is provided at each end with the arms I, by means of which the knife-head is pivot-

ally secured at *b* to the upper end of the shifting bar J and to one end of the link K, the other end of which is pivotally secured at *c* to the frame of the machine. The lower end of the shifting bar J is pivotally secured to a 55 wrist, *d*, on the rock-arm L. This rock-arm is secured upon the rock-shaft L', which is journaled in bearings longitudinally of the frame, and another wrist-pin, *e*, on the rock-arm L engages into a cam-groove, *f*, formed 60 on the upper end of the vibrating lever M. This vibrating lever has a fixed fulcrum at *g*, and is pivotally connected at its lower end at *h* with the free end of the eccentric-rod N. This eccentric-rod has its actuating eccentric N' secured upon a shaft, O, to which is secured the gear-wheel P. This gear-wheel meshes with the gear-pinion Q upon the main drive-shaft R of the machine, and by means of the eccentric S, secured upon this drive-shaft, and the eccentric-rod S', actuated thereby and pivotally connected with its free end to the wrist *i* on the side of the knife-head, a reciprocating motion is communicated to the knife, which motion is on the arc of a circle having pivots *b* for the fulcrum. The relative diameters of the drive-pinion Q and the gear-wheel P being as one to two, the knife will make two strokes to one revolution of the eccentric N', while the lever M, actuated by said eccentric, will make two vibrations at the same time, thus carrying the wrist-pin *e* of the rock-arm L from one end of the cam-groove to the other. This cam-groove is 75 so formed as to rock the rock-arm L and thereby shift the pivot *b* by means of the connection J from one of the two positions, as shown in Figs. 5 and 6, where one position is shown in full lines and the other is shown in dotted lines. This shifting of the pivots of the knife-head causes an alternate tilting of the knife, 80 so that while one hoop is cut with a bevel upward, the next hoop will be cut with the bevel downward, and so on alternately.

The plank is fed by the operator against the stops T, which reciprocate in vertical bearings at the rear side of the cutting-block, and these stops T are secured to the common head U, which extends horizontally, and is connected at its rear end, by means of the links V, to the knife-head, so that the reciprocating motion 85 90 95 100

of the knife-head raises and lowers the stops in a proper manner to enable the operator to adjust the plank against the stops and at the same time to throw them out of the way as soon as the hoop is cut, to permit of having said hoop removed by means of the oscillating arms *W*, which are secured upon the shaft *W'*, which is provided upon its ends with the rock-arm or rock-arms *j*, which by means of the connecting-link *k* are connected to the rock-arm *l* upon the shaft *L'*, all so arranged that by means of this connection a single vibration is given to the arms *W* to remove the hoop from the rear end of the bed as soon as it is cut.

15 It will be seen from Fig. 6 that the motion of the knife being in the arc of a circle, one side of the hoop will be cut slightly concave, and this I consider imparts an improved quality to the hoop to better hold it upon the barrel, provided it is placed with its concave side toward the barrel, and I believe these hoops to be a new and improved article of manufacture, which have never heretofore been made with any hoop-machine of this class nor of any other kind.

20 As it is often required to alter the thickness of the hoops, I provide all the parts, where necessary to effect the object, with the necessary adjustment, which may be of any desired construction.

25 What I claim as my invention is—

1. The combination, with the frame and bed of a hoop-cutting machine, of a knife and its head and means, as the eccentrics *N'* and *S* and intermediate connections, for giving said knife a curvilinear cutting motion in different paths alternately, substantially as described.
2. The combination, with the frame and bed of a hoop-cutting machine, of a knife attached to a head mounted on a movable pivot and means, as the eccentrics *N'* and *S*, for moving said pivot in opposite directions and the knife in a curvilinear direction in different paths alternately, substantially as described.
3. The combination, with the frame and stationary bed of a hoop-cutting machine, of the knife-head constructed and arranged to carry the knife in the arc of a circle in different paths alternately, the arms *I* moving in the

same plane at each stroke, and pivot *b*, on which said arms work, reciprocating in a straight line to and from the paths of the knife, the wrists *i* on arms *I*, the main drive-shaft *R*, the eccentrics *S* on said shaft, and the eccentric-rods *S'*, secured to the wrists *i*, and all arranged to operate substantially as described.

4. The combination, with the frame, knife, and bed of a hoop-cutting machine, of a reciprocating head, *H*, arms *I*, carrying said head and moving always in the same plane and pivoted on a movable fulcrum, *b*, and means, as the eccentrics *N'* and *S* and intermediate connections, for changing the position of the fulcrum, and thus giving the knife a curvilinear reciprocating motion in different paths alternately, substantially as described.

5. The combination, in a hoop-cutting machine, of the following elements: a stationary table, a cutting-knife mounted to reciprocate in the arc of a circle, a knife-head pivotally secured and carrying said knife, a cutting-block secured in the rear end of the table, two or more vertically-reciprocating stops at the rear end of the table, two or more vibrating arms to remove the cut hoops from the table, mechanism for reciprocatingly actuating the knife, and mechanism for shifting the pivots of the knife-head alternately into one of two positions, substantially as described.

6. The combination, in a hoop-cutting machine, of the stationary table, the cutting-knife reciprocating in the arc of a circle, the knife-head pivotally secured and carrying the cutting-knife, the main drive-shaft *R*, the counter-shaft *O*, the eccentric *N'*, the lever *M*, connected to the eccentric and provided with the cam-groove *f*, the rock-arm *L* on the rock-shaft *L'*, and the links *J K*, the parts being arranged and constructed to operate substantially as described.

In testimony whereof I affix my signature, in presence of two witnesses, this 27th day of April, 1888.

ALEXANDER F. WARD.
